UNITED STATES PATENT OFFICE.

JAMES L. BANCROFT, OF CLEVELAND, OHIO, ASSIGNOR TO THE OHIO BODY & BLOWER COMPANY, OF CLEVELAND, OHIO, A CORPORATION OF OHIO.

AUTOMOBILE BODY CONSTRUCTION.

Application filed June 9, 1920. Serial No. 387,545.

To all whom it may concern:

Be it known that I, JAMES L. BANCROFT, a citizen of the United States, residing at Cleveland, in the county of Cuyahoga and State of Ohio, have invented a certain new and useful Improvement in Automobile Body Construction, of which the following is a full, clear, and exact description, reference being had to the accompanying drawings.

This invention relates to improvements in automobile body construction.

Heretofore it has been the practice to finish the top edges of the doors and the corresponding edges of the sides and cowl and other similar parts of automobile bodies by flanging the corresponding edge portions of the plates or panels which constitute the covering of the body over the adjacent edges of the frames. This has required much skill and consumed much time, and in places where the contour of the body presented compound curves, the work was exceedingly difficult and the results often unsatisfactory.

Pursuing this method, the lining panels were applied to the inner sides of the frame with their edges adjacent the flanged over edges of the outer plates and tape or binder was secured along the edges of the liner panels to produce a finished effect.

Now it is the fundamental object of my invention to eliminate these operations and thereby greatly expedite manufacture, release skilled labor for other duties and materially cheapen production by providing a molding of channel formation for finishing the top edges of the doors, sides, etc., which is designed to fit over the edge of the frame and embrace the adjacent edges of the inner and outer plates or panels with the following advantages: It strengthens the construction; improves its appearance; makes practically unnecessary the use of additional holding means for the top edges of the inner and outer panels; or in case the use of additional holding means, such as tacks or screws, is deemed advisable, it conceals such means and any deformation or puckering of the panels resulting therefrom; and it makes possible a very neat joint between the door and jamb by allowing the molding to be applied in a continuous piece to the edges of these parts and then cut accurately on the line of division between the door and jamb;

and, in case the top edges of the door and jamb do not align properly, as if the door should sag slightly or be a little high, the molding on the part that is lower may be raised to compensate for the irregularity.

With the foregoing in mind, a brief specific description of the embodiment illustrated in the drawing will suffice to impart to those skilled in the art a clear understanding of the invention.

In the drawing, Fig. 1 is a fragmentary side elevation of an automobile incorporating my improved body construction; Fig. 2 is a detail showing the construction, the view being taken in the region of the joint between the door and jamb; Fig. 3 is a section on the line 3—3 of Fig. 2; and Fig. 4 is a fragmentary perspective view of the molding.

In the present instance, the top edges of the cowl, door, side and seat back of the automobile shown in Fig. 1 are finished with a molding A. In Figs. 2 and 3, the door frame is designated 1, and it has plates or panels 2 and 3 applied to its outer and inner sides, respectively. The molding A, which is of channel formation, is applied to the top of the frame and its side flanges engage snugly over the plates or panels 2 and 3, and serve to hold them securely against the frame.

If desired, additional holding means may be employed for securing the top edges of the panels to the frame, and this would be preferable in cases where the inner panel is of leather or other flexible finishing material. In case such holding means are employed, the side flanges of the holding conceal them and any deformation of the panels resulting from their use.

In Fig. 2 I have shown the frame of the door sagged slightly below the frame 1^a of the side. The piece of molding that is applied to the door is raised to the plane of that mounted on the side by a shim 8 that is inserted between the web of the panel 10 and the top of the frame. The molding may be held in place by screws 10 passing through holes in its web and threaded into the frame; and in the present instance one of these screws is shown as holding the shim 8 in place.

The molding is preferably made of ductile or pliant material so that it may be bent

readily to conform to the shape of the frame.

Having thus described my invention, what I claim is:

1. In automobile body construction, the combination of a frame, a panel applied to the side of the frame, means for securing the panel to the frame and a molding engaged over the edge of the frame and having a flange overlying the adjacent edge portion 10 of the panel and concealing said securing means.

2. In auto body construction, the combination of a frame, panels applied to opposite

sides of the frame, securing means attaching the edge of one or both of the panels to 15 the frame, a channel moulding engaged over the edge of the frame and embracing the adjacent edge portions of the panels and concealing the aforesaid securing means and securing means extending through apertures in the web of the moulding and entering the frame.

In testimony whereof, I hereunto affix my signature.

JAMES L. BANCROFT.
